UNITED STATES PATENT OFFICE

WALTER VAN B. ROBERTS, OF PRINCETON, NEW JERSEY, ASSIGNOR TO RADIO CORPORATION OF AMERICA, A CORPORATION OF DELAWARE

TUNED RADIO FREQUENCY RECEIVER

Application filed March 30, 1929. Serial No. 351,407.

This invention relates to tuned radio frequency receiving circuits, and, more particularly, to a tuned radio frequency circuit in which the coupling is varied coincidently with the tuning of the circuit.

The characteristics of a stage of tuned radio frequency are first, amplification; second, selectivity; and third, the manner in which these quantities vary with frequency. The amount of regeneration should also be considered, but this factor is really included in the amplification and selectivity. The maximum non-regenerative amplification of any circuit is limited by the tube constants and the coil efficiencies. Almost any design of radio frequency amplifier can be made to operate ideally at all frequencies, if the coupling means is varied simultaneously with the tuning.

Selectivity is limited by coil efficiency, and is further reduced by the coupling to the tube, there being a decided loss in selectivity if the coupling is adjusted for a maximum amplification, but very little loss of selectivity occurring if the coupling is adjusted for a reasonable fraction, e. g. three-quarters of maximum amplification. Hence, in any type of amplifier, and at any frequency, the coupling determines what compromise there should exist between maximum amplification and maximum selectivity.

By having the coupling vary in a predetermined manner with frequency, it is possible to maintain maximum amplification at all frequencies (which results in varying selectivity), or uniform voltage amplification at all frequencies (which leaves the selectivity more nearly constant), or other desired characteristics. If, in addition, the amount of regeneration, (or in other words, departure from exact neutralization), varies in a predetermined fashion with frequency, I can achieve uniform selectivity along with the desired amplification characteristic.

Accordingly, it is one of the main objects of my present invention to provide means in a tuned radio frequency circuit, in addition to the usual tuning means, to secure a predetermined performance, for example, uniform

voltage amplification, and contact band width selectivity.

Another important object of the present invention is to provide means for securing ideal performance of a tuned radio frequency receiving circuit in which the coupling in said circuit is varied simultaneously in a predetermined manner with the usual tuning means.

The novel features which I believe to be characteristic of my invention are set forth in particularity in the appended claims, the invention itself, however, as to both its organization and method of operation will best be understood by reference to the following description taken in connection with the drawing in which I have indicated diagrammatically two circuit organizations whereby my invention may be carried into effect.

In the drawing:—

Figure 1 shows a circuit embodying my invention; and

Figure 2 shows a modified form of the invention.

The circuit indicated in Figure 1 comprises a receiving circuit with the usual antenna circuit, and includes a stage T of radio frequency amplification and a detector D for the sake of simplicity of showing. The detector D is connected to any type of utilization means. The radio frequency stage T is coupled to a primary coil P in the antenna circuit by means of a secondary coil S, the latter forming with variable condenser C₁ a tuned input circuit for the stage T.

In the same manner the secondary coil S₁ of the input circuit of detector D, forms with variable condenser C₂ a tuned input circuit for the detector. The condensers C₁, C₂ are mounted on a common shaft in any well known manner, shown on the drawing in dotted lines for the sake of simplicity, the common shaft being geared to a shaft 6. It is understood, of course, that the condenser shaft is operated by uni-control means (not shown), and that the uni-control tuning means is employed herein.

The coupling between coils P and S is maintained at the required value at each frequency by the rotation of a properly de-

signed shield 1 mounted on an adjustment shaft 3, the latter being geared, by means of a bevelled gear 8, to a bevelled gear 7 mounted on the shaft 6. This results in the maintenance of a fixed relation between the adjustment shaft 3 and the tuning means of the receiving circuit.

The shield 1 is preferably made of copper, but may be made of any other metal suitable for the purpose. The shield 1 may be positioned between P and S, in which case, it not only varies the coupling, but also reduces the apparent inductances of P and S at high frequency. This is advantageous since the first reduction lessens the tendency toward oscillation in the case of inter-tube transformers, and the second reduction increases the tuning range since the reduction occurs at the high frequency end of the tuning range. Of course, the shield may be on the other side of coil P, and, in that case, it does not affect the inductance of S appreciably.

A second shield 2, also preferably made of copper, is mounted on the shaft 3 for rotation between the coils P₁, S₁, and is designed in a manner similar to the shield 1. Neutralization is complete or partial depending upon the capacity of the plates 4, 5. The plate 4 is fixed and connected at one end to a coil N, the latter being coupled for reversed feed back (that is, reversed with respect to feed back via plate-grid capacity) to the coil S.

The capacity of the members 4, 5 depends on the shape of the rotor plate 5, the plate being mounted on the adjustment shaft 3 for rotation therewith, and the shape is such as to give the desired amount of neutralization at each frequency. The shaft 3 is ground, and operates simultaneously with the movement of the uni-control tuning means. The coupling between the neutralizing coil N and the coil S is of any convenient value and is fixed. It is, however, possible to substitute a fixed capacity for plates 4 and 5 and then vary the coupling between N and S, preferably by a properly shaped copper shield rotating on shaft 3 between the coils, in similar fashion to shield 1.

Exactly the same mechanism may be used wherever tuned radio frequency amplification occurs, it being understood that the shapes of the shields 1, 2, and neutralizing condenser plates 4, 5 are to be changed according to the particular requirements. For example, in a superheterodyne it would be desirable to stress maximum amplification rather than selectivity, because the selectivity is obtained in the intermediate frequency amplifier. On the other hand, in a tuned radio frequency receiver having many tubes, such as the present broadcast receivers, I preferably design the plates to give equal selectivity at all settings as the amplification is likely to be greater than necessary.

The operation of the mechanism should be obvious from the above description and drawing, it being understood that the shields 1, 2, and the condenser plates 4, 5 are so designed that for each frequency setting secured by rotation of the condenser common shaft, the adjustment shaft 3 simultaneously is brought into position to produce a coupling between the coils P, S, and the coils P₁, S₁, whereby the desired amplification and selectivity are secured for the said particular frequency, it also being observed that the departure from exact neutralization varies in a predetermined fashion with the frequency due to the adjustment of the plates 4, 5, coincidently with the tuning means.

It is to be noted that the various shields and plates may be mounted on the same shaft that carries the rotors of the tuning means, in order to eliminate the gearing required to operate a second shaft.

In Fig. 2, there is shown another embodiment of the invention for maintaining uniform voltage amplification in stages employing tubes of the screen grid alternating current type. As shown, the signal energy is fed into a tube 1, the latter including a filament 3 indirectly heated by a heater element 4 which is connected to the alternating current supply mains through a transformer 5, the midpoint of the transformer secondary being grounded, as is well known in the art.

The signal energy is fed into the grid-filament circuit through a resistance R in series with the filament, in a manner well known by those skilled in the art. The plate current is fed through a choke coil 6 from a source of direct current "B", the source "B" being also tapped at a proper point to positively bias the screen elements 7 of tubes 1 and 2, it being noted that the filament 3 of tube 2 is heated indirectly from the same alternating current source as tube 1.

The output circuit of tube 1 is coupled to the tuned input circuit of tube 2 by a condenser 8 of small capacity. This capacity may be, for example, approximately 20 micro-micro-farads. The tuned input circuit of tube 2 includes the inductance 9 and variable capacity connected in parallel.

Some magnetic coupling between choke 6 and coil 9 may be used, but it is not essential. With this arrangement, choke 6 preferably having a natural wave length greater than that of any of the desired signals, fairly uniform voltage amplification is obtained.

To make the amplification perfectly uniform, a variable capacity 11 is connected across the choke coil 6 and source "B" in such a manner that it is in parallel with the distributed capacity 12 of the choke coil 6, the capacity 12 being shown in dotted lines. It is to be noted that the condenser 11 is mounted so that its rotor is uni-controlled along with the shaft 13 (shown as a dotted

line) upon which shaft the rotor of tuning condenser 10 is mounted.

The plates of condenser 11 are designed so as to give the greatest capacity where the amplification would otherwise be greatest. It has been ascertained by experiment that at any frequency the amplification may be reduced to the extent required to maintain the desired uniformity, by having the condenser 11 of a very small capacity of the order of 10 micro-micro-farads or less. Thus by this arrangement, no mechanical difficulty is encountered in providing a condenser that will have the proper capacity at such frequency.

While I have indicated and described only two systems for carrying my invention into effect, it will be apparent to one skilled in the art that my invention is by no means limited to the particular organizations shown and described, but that many modifications in the circuit arrangements, as well as in the apparatus employed, may be made without departing from the scope of my invention as set forth in the appended claims.

What I claim is:

1. In a receiving circuit a space discharge device having an anode, a cathode, a control electrode and a shielding electrode, a source of current and a choke coil in series connected between the anode and the cathode, a second space discharge device having a tuned input circuit and an output circuit, said tuned input circuit comprising a variable capacity, a condenser for connecting the anode of said first mentioned space discharge device to one side of said variable condenser, a second variable condenser shunted across said choke coil and said current source, one side of each of said variable condensers and one side of said current source being grounded.

2. In a receiving circuit, a space discharge device having an anode, a cathode, and a control electrode, a circuit comprising a source of current and a choke coil in series connected between the anode and cathode of said space discharge device, said circuit having a natural wave length greater than that of any signals desired to be received, a second space discharge device having a tuned input circuit, said tuned input circuit comprising a variable condenser, a capacity for coupling the anode of said first mentioned space discharge device to the control electrode of said second named device, a second variable condenser shunted across said choke coil, and means for connecting one side to each of said variable condensers and one terminal of said current source to ground.

3. In a receiving circuit, a space discharge device having an anode, cathode, and a control electrode, a circuit comprising a source of current and a choke coil in series connected between the anode and cathode of said space discharge device, said circuit having a natu-

ral wave length greater than that of any signals desired to be received, a second space discharge device having a tuned input circuit, said tuned input circuit comprising a variable condenser, a coupling condenser for connecting the anode of said first mentioned space discharge device to one side of said variable condenser, a second variable condenser shunted across said choke coil, one side of each of said variable condensers and one terminal of said current source being grounded.

4. In a receiving circuit, an electron discharge device having a cathode, an anode and a control electrode, a coil having inherent distributed capacity, connected between said anode and said cathode forming a circuit having a natural wave length greater than that of any signals desired to be received, a variable condenser connected in parallel with the inherent capacity of the coil, said variable condenser having a capacity of the order of magnitude of 10 micro-micro-farads, a second space discharge device having a tuned input circuit comprising an inductance coil and a variable tuning condenser, a coupling condenser connected between one end of said first named coil and one end of said tuned input circuit and means for simultaneously varying said two variable condensers.

5. In a receiving circuit an electron discharge device having a cathode, an anode, a control electrode and an auxiliary electrode, a coil and a source of current in series connected between said anode and said cathode, said coil having sufficient inherent distributed capacity to form a circuit having a natural wave length greater than that of any signals desired to be received, a connection between said auxiliary electrode and a point of said source of intermediate potential, a variable condenser connected across said coil and current source, a second space discharge device having a cathode, an anode, a control electrode and an auxiliary electrode, a tuned circuit comprising an inductance and a variable condenser connected across the control electrode and the cathode of said second device, means for connecting said two cathodes to ground, means for simultaneously varying both said variable condensers and a coupling means comprising a condenser connected between the anode of said first named device and the control electrode of said second named device.
